United States Patent Office

Des. 180,919

Patented Sept. 3, 1957

180,919

PHOTOGRAPHIC UNIT

Ernest P. Taubes, Rochester, N. Y.

Application December 7, 1956, Serial No. 44,107

Term of patent 14 years

(Cl. D61—1)

Fig. 1

Fig. 2

Fig. 3

Fig. 4

Fig. 5

Fig. 2 is a perspective view of a photographic unit, showing my new design;

Fig. 2 is a vertical section through the same unit, taken approximately on the line 2—2 of Fig. 3, showing part of the unit in vertical section and most of it in front elevation;

Fig. 3 is a side elevation of the unit, viewed from the right hand side;

Fig. 4 is a rear elevation thereof; and
Fig. 5 is a top plan thereof.

I claim:

The ornamental design for a photographic unit, substantially as shown.
